UNITED STATES PATENT OFFICE.

GUIDO FORNACA, OF TURIN, ITALY.

INTERNAL-COMBUSTION ENGINE.

Application filed November 26, 1927, Serial No. 235,952, and in Italy August 23, 1927.

This invention relates to valve gearings for engines having several groups of cylinders, said groups being located side by side, parallel with each other and having each a crank shaft, which crank shafts are parallel with each other. In engines of this kind the several crank shafts are interconnected by a toothed gearing including a member which transmits the drive to a driving shaft or to 10 a propeller or the like, in motor cars, aircraft, and the like.

The invention has for its object to provide an engine of the kind above referred to, in which the cylinders of two adjacent groups 15 are arranged in such a manner that the valves of the same character (as inlet valves) in the cylinders of said adjacent groups face one another. Between said facing valves is mounted a cam shaft which operates the said 20 valves of like character in both groups of cylinders; the valves of other character being located on the remote sides of the cylinder groups and being controlled by another common cam shaft.

Moreover, in the present invention the cam shaft serving two groups of cylinders comprises a number of cams which equals the 25 number of cylinders of a single group, and all the cam shafts of the engine are identical 30 with one another and consequently are interchangeable.

In the accompanying drawings is illustrated by way of example one embodiment of this invention and

35 Figure 1 is a cross section of the engine; Figure 2 is a diagram of the drive of the cam shafts;

Figure 3 is a diagram of the arrangement of the parts of the engine.

40 In the embodiment illustrated, the engine comprises two parallel groups of cylinders I-II having their axes parallel with each other, said cylinders being arranged in line on a common crank casing 22; each group 45 comprises six parallel and aligned cylinders and has a crank shaft 23, 24 with six cranks at 120° each other.

The crank shafts 23-24 are connected by rods 25-26 with pistons 27-28 reciprocating in cylinders I-II, and said shafts have 50 pinions 29-30 respectively which mesh with an intermediate pinion 17 rigidly secured to a shaft 16 intended for driving connection with a propeller, wheel shaft or the like.

55 In accordance with this invention, the cyl-

inders of the left hand Group I have their valves 7' of one character (as their inlet valves) on the right side, while the inlet valves 7" of the right hand Group II of cylinders are located on the left side, they being 60 thus close to and in front of valves 7' of the cylinders of Group I.

Intermediate said valves and cooperating therewith is arranged a cam shaft 8 comprising six cams 10, and each of these cams operates the inlet valves of adjacent cylinders of 65 said two groups, the axis of the valves of like character in the adjacent cylinders of adjacent and parallel groups being located in the same transverse plane (see cylinders 70 2'-1, 6'-5, 4'-3, 1'-6, 3'-2, 5'-4 in Fig. 3).

This result is obtained in this engine (which is assumed to be a four-stroke cycle one, with ignition taking place in the order 75 1-1'-2-2'-3-3'-4-4'-5-5'-6-6' (Fig. 3)) by arranging rocking arms 9'-9" in such a manner that the phases of the valve of one of the cylinders of the transverse pair are displaced through 60° with respect to the 80 phases of the valve of the other cylinder of the same pair.

The cam shafts 11', 11" which operate 85 rocking arms 13', 13" of the exhaust valves 14', 14", comprise cams 15', 15" having the same phase and extent as cams 10 of shaft 8, and the three shafts 8-11'-11" rotate in the same direction, being driven from shaft 16 by gearings 17', 18, 19, 20', 21', 20", 21"; consequently the three cam shafts 8- 90 11'-11" are alike and they may be replaced one by another, this being of course a great advantage in practice.

The described arrangement may of course be embodied in engines having more than two 95 groups of cylinders; in such case, in the several pairs of cylinder groups the adjacent valves have the same function and they are operated by a single intermediate cam shaft, the external sets of valves being operated 100 each by a separate cam shaft.

What I claim as my invention and desire to secure by United States Letters Patent is:—

1. An engine comprising a plurality of 105 groups of cylinders, said cylinders being parallel and aligned in each group and the several groups being parallel and adjacent to each other, valves in said cylinders, the valves of the same character being provided 110

in portions of cylinders of said groups facing each other, a cam shaft arranged intermediate each pair of adjacent groups and actuating said facing valves, the other valves of the cylinders being located in portions of the cylinders which are remote from each other, and a cam shaft for each set of last named valves.

2. An engine comprising a plurality of groups of cylinders, said cylinders being parallel and aligned in each group and the several groups being parallel and adjacent to each other, valves in said cylinders, the valves of the same character being provided in portions of cylinders of said groups facing each other, a cam shaft arranged intermediate each pair of adjacent groups and actuating said facing valves, said cam shaft having a number of cams equal to the number of cylinders of a single group, the other valves of the cylinders being located in portions of the cylinders which are remote from each other, and a cam shaft for each set of last named valves.

3. An engine comprising a plurality of groups of cylinders, said cylinders being parallel and aligned in each group and the several groups being parallel and adjacent to each other, valves in said cylinders, the valves of the same character being provided in portions of cylinders of said groups facing each other, a cam shaft arranged intermediate each pair of adjacent groups and actuating said facing valves, said cam shaft having a number of cams equal to the number of cylinders of a single group and each of said cams operating the facing of two transversely aligned cylinders of said groups, the other valves of the cylinder being located in portions of the cylinders which are remote from each other, and a cam shaft for each set of last named valves.

4. An engine comprising a plurality of groups of cylinders, said cylinders being parallel and aligned in each group and the several groups being parallel and adjacent to each other, valves in said cylinders, the valves of the same character being provided in portions of cylinders of said groups facing each other, a cam shaft arranged intermediate each pair of adjacent groups and actuating said facing valves, the other valves of the cylinders being located in portions of the cylinders which are remote from each other, a cam shaft for each set of last named valves, and means driving all said cam shafts in the same direction.

5. An engine comprising a plurality of groups of cylinders, said cylinders being parallel and aligned in each group and the several groups being parallel and adjacent to each other, said cylinders having like inlet and exhaust phases, valves in said cylinders, the valves of the same character being provided in portions of cylinders of said

groups facing each other, a cam shaft arranged intermediate each pair of adjacent groups and actuating said facing valves, the other valves of the cylinders being located in portions of the cylinders which are remote from each other, a cam shaft for each set of last named valves, all said cam shafts being interchangeable with one another, and means driving all said cam shafts in the same direction.

6. An engine comprising a casing, a plurality of rows of cylinders on said casing, the cylinders of each row being parallel with each other and said rows being arranged in parallel lines on said casing, a crank shaft for each of said cylinder rows, pistons in said cylinders and rods connecting the pistons of the cylinders of one of said rows with the cranks of the respective crank shaft, valves in said cylinders, the valves of the cylinders of one row having the same character as the valves facing them in the cylinders of an adjacent parallel row, a cam shaft intermediate each pair of cylinder rows and having cams actuating said valves of the same character, the other valves of the cylinders being located in the remote portions of the rows of cylinders, cam shafts each actuating the last named valves of a cylinder row, and driving means intergearing said cam shafts and crank shafts.

7. An engine comprising a casing, a plurality of rows of cylinders on said casing, the cylinders of each row being parallel with each other and said rows being arranged in parallel lines on said casing, a crank shaft for each of said cylinder rows, pistons in said cylinders and rods connecting the pistons of the cylinders of one row with the cranks of the respective crank shaft, valves in said cylinders, the valves of the cylinders of one row having the same character as the valves facing them in the cylinders of an adjacent parallel row, a cam shaft intermediate each pair of cylinder rows having cams actuating said valves of the same character, the other valves of the cylinders being located in the remote portions of the rows of cylinders, cam shafts each actuating the last named valves of a cylinder row, and driving means intergearing said cam shafts and crank shafts.

8. An engine comprising a casing, a plurality of rows of cylinders on said casing, the cylinders of each row being parallel with each other and said rows being arranged in parallel lines on said casing, a crank shaft for each of said cylinder rows, pistons in said cylinders and rods connecting the pistons of the cylinders of one row with the cranks of the respective crank shaft, valves in said cylinders, the valves of the cylinders of one row having the same character as the valves facing them in the cylinders of an adjacent parallel row, a cam shaft intermediate each pair of cylinder rows having cams actuating

5 said valves of the same character, said cams being equal in number to the number of cylinders of a single row, the other valves of the cylinders being located in the remote portions of the rows of cylinders, cam shafts each actuating the last named valves of a cylinder row, and driving means intergearing said cam shafts and crank shafts.

9. An engine comprising a casing, a plurality of row of cylinders on said casing, the cylinders of each row being parallel with each other and said rows being arranged in parallel lines on said casing, a crank shaft for each of said cylinder rows, pistons in said 10 cylinders and rods connecting the pistons of the cylinders of one row with the cranks of the respective crank shaft, valves in said cylinders, the valves of the cylinders of one row having the same character as the valves 15 facing them in the cylinders of an adjacent parallel row, said cylinders having like inlet and exhaust phases, a cam shaft intermediate each pair of cylinder rows having cams actuating said valves of the same character, 20 the other valves of the cylinders being located in the remote portions of the rows of cylinders, cam shafts each actuating the last named valves of a cylinder row, and means intergearing said cam shafts and crank shafts to drive 25 all said cam shafts in the same direction, all said cam shafts being interchangeable with one another.

10. An engine comprising a casing, a plurality of rows of cylinders on said casing, the 30 cylinders of each row being parallel with each other and said rows being arranged in parallel lines on said casing, a crank shaft for each of said cylinder rows, pistons in said cylinders and rods connecting the pistons of the 35 cylinders of one row with the cranks of the respective crank shaft, valves in said cylinders, the valves of the cylinders of one row having the same character as the valves facing them in the cylinders of an adjacent parallel row, said cylinders having like inlet and 40 exhaust phases in both rows and the phases of operation of said valves being displaced 60° from one another, a cam shaft intermediate said cylinder rows having six cams at 60° apart and actuating said valves of the same character in both rows of cylinders, the other 45 valves of the cylinders being located in the remote sides of the cylinders of said rows, cam shafts each having six cams at 60° apart and actuating the last named valves of one of said rows, and means intergearing said cam shafts and crank shafts to drive all said cam shafts in the same direction, said cam shafts being all interchangeable with one another.

exhaust phases, a cam shaft intermediate each pair of cylinder rows having cams actuating said valves of the same character, said cams being equal in number to the number of cylinders of a single row, the other 50 valves of the cylinders being located in the remote portions of the rows of cylinders, cam shafts each actuating the last named valves of a cylinder row, and means intergearing said cam shafts and crank shafts to drive 55 all said cam shafts in the same direction, all said cam shafts being interchangeable with one another.

11. An engine comprising a casing, two rows each of six cylinders on said casing, the 60 cylinders in each row being parallel with each other and said rows being arranged in parallel lines on said casing, a crank shaft for each cylinder row and pivoted in said casing, said crank shafts having each six cranks 65 at 120° apart, pistons in said cylinders and rods connecting the pistons of the cylinders of each row with the cranks of the respective crank shaft, valves in said cylinders, the valves of the cylinders of one row having the 70 same character as the valves facing them in the cylinders of the adjacent parallel row, said cylinders having like inlet and exhaust phases in both rows and the phases of operation of said valves being displaced 60° from 75 one another, a cam shaft intermediate said cylinder rows having six cams at 60° apart and actuating said valves of the same character in both rows of cylinders, the other 80 valves of the cylinders being located in the remote sides of the cylinders of said rows, cam shafts each having six cams at 60° apart and actuating the last named valves of one of said rows, and means intergearing said cam shafts and crank shafts to drive all said cam shafts in the same direction, said cam shafts being all interchangeable with one another.

In testimony whereof I affix my signature.

GUIDO FORNACA.
